United States Patent Office.

JAMES MOORE, OF ERGINETH, IRELAND.

Letters Patent No. 101,645, dated April 5, 1870.

IMPROVEMENT IN FIRE-PLACES.

The Schedule referred to in these Letters Patent and making part of the same

To all whom it may concern:

Be it known that I, JAMES MOORE, of Ergineth, in the county of Tyrone, Ireland, have invented new and useful Improvements in Grates, Stoves, and Furnaces; and I do hereby declare the following to be a clear and exact description of the nature thereof, sufficient to enable others skilled in the art to which my invention appertains to fully understand and use the same, reference being had to the accompanying drawings making part of this specification, in which—

Figure 1 is a front view of a grate having my invention applied thereto.

Figure 2 is a top or plan thereof.

Figure 3 is a central vertical section.

Figure 4 is a central horizontal section in line $\alpha\alpha$, fig. 3.

Similar letters of reference indicate corresponding parts in the several figures.

My invention consists in heating air by admitting it in a fresh state below the fire-chamber into a receiving-chamber and one or more tubes therein, in connection with one or more tubes in the fire-chamber communicating with the receiving-chamber, so that the air from the several points may be united in a heated condition and discharged.

In the drawings—

A represents the fire-plate, and B B, the side plates, and E, the rear plate, which are constructed and arranged to form a hot-air chamber, D.

The rear plate E may be dispensed with, and in lieu thereof I may employ slate or brick, and extend it from the flange N at the top of the chamber D to the brick-work around the fire-place, and coat such brick or slate roof with mortar or other cement, to prevent the escape of hot air into the chimney.

F represents a tube, which extends into the chamber D, and communicates with one or more tubes, G, which are arranged within the combustion-chamber K.

The ends of the tube pass through the side pieces B, and communicate with the chamber D.

It will be seen that the air is admitted into the chamber D and the pipe F beneath the plate P at space C.

Such air as enters pipe F passes into the tube G, where it is heated, and thence into the chamber D.

The air that enters the chamber D from below is heated in its upward passage by contact with the plates A B, which are naturally heated by the fire in the grate.

The hot air in the chamber D is discharged into the room at the points I or H, or other suitable localities.

There is a constant current of air from the entrance into the chamber D to its exit therefrom. It takes the cold air from the room or apartment, and discharges it again in a heated state.

O represents a removable regulator or fender, which is to be placed across the face-plate in front of the fire-chamber K, and extending sufficiently high to cover the lower part of said fire-chamber.

M represents flanges, which secure the fire and side plates to the face-plate, and prevent the escape of gases into the hot-air chamber.

The pipes F and G may be differently arranged, and multiplied, as desirable; but it is intended that they assist in heating the air, which will be seen is heated by two operations, namely, such as passes directly into the chamber D from the space C, and comes in contact with the heated plates A B, and such as enters into the chamber through pipes F G.

Having thus described my invention,

What I claim as new, and desire to secure by Letters Patent, is—

1. The receiving-chamber, and one or more tubes therein, in connection with one or more tubes in the fire-chamber communicating with the receiving-chamber, so that the air from the several points may be united in a heated condition and discharged.

2. The vertical tube or tubes F, arranged within the air-chamber D, substantially as and for the purpose described.

The above signed by me this 5th day of January, 1870.

Witnesses:

JAMES MOORE.

JOHN A. WIEDERSHEIM,
SMITH DEXTER, Jr.
